UNITED STATES PATENT OFFICE.

ELIJAH F. JOHNSON, OF UNION MILLS, NORTH CAROLINA.

CONNECTING-ROD FOR SWITCHES.

1,077,141.

Specification of Letters Patent. Patented Oct. 28, 1913.

Application filed December 10, 1912. Serial No. 736,008.

To all whom it may concern:

Be it known that I, ELIJAH F. JOHNSON, a citizen of the United States, residing at Union Mills, in the county of Rutherford 5 and State of North Carolina, have invented new and useful Improvements in Connecting-Rods for Switches, of which the following is a specification.

This invention relates to railroad switches, the object being to provide adjustable means for connecting the movable switch points with the switch-stand mechanism whereby proper adjustment of the switch points may be effected at all times 15 to insure proper operation thereof and to prevent lost motion.

A further object of the invention is to provide adjustable means connecting the movable switch points with each other and 20 with the said stand to allow for the relative movement of the switch points with each other and with the connecting rod extending to the switch stand.

With these and other objects in view, the 25 invention consists of certain novel features of construction, combination and arrangement of parts, as will be hereinafter described and claimed.

In the accompanying drawings:—Figure 30 1 is a plan view of the device; Fig. 2 is a transverse sectional view, taken on the line 2—2 of Fig. 1; and Fig. 3 is a longitudinal sectional view through one of the adjustable connecting members.

35 In the drawings, the numerals 1 and 2 designate the movable switch points. A transversely extending rod 3 is secured to the switch point 2 adjacent its free end and has its inner end screw-threaded as at 4, 40 this end of the rod being threaded into a transverse threaded opening 5 in the bolt portion 6 of an adjustable connecting member 7. This bolt portion is rotatably mounted between the arms of a yoke-shaped cuff- 45 portion 8 of the connecting member. The curved connecting portion 9 of this cuff is of sufficient size and rigidity to retain its semi-circular shape, and is provided with an arcuate slot 10. A second rod 11 extends 50 transversely through the switch point 1 adjacent its free end and has both of its ends oppositely screw-threaded as at 12 and 13, the threads at 12 being opposite to the threads at 4 on the rod 3. Its inner threaded end 13 is adapted to be extended through 55 the threaded opening 14 in the second yoke

member 15, which forms a portion of the connecting member and which is provided with transverse slots 16 in its arms for the slide- 60 able reception of the curved portion 9 of the cuff 8, the said rod being extended further through the arcuate slot 10 in the cuff 8. The bolt portion of a similar connecting member 17 is adjustably connected to the oppositely threaded end 13 of the rod 65 11 and the cuff-portion of this member is adjustably connected to the threaded end 18 of a connecting rod 19 which extends to the crank 20 of the stand mechanism 21. It will thus be seen that, when it is desired to ad- 70 just the movable switch points with relation to each other so as to insure proper engagement thereof with the track rails, it is merely necessary to rotate the cuff 8 of the connecting member disposed therebetween 75 by the application of a bar of some sort, which may be inserted between the arms thereof. When the switch points are thrown into either of their operative positions, the said switch points will swing in circles 80 whose centers are spaced from each other, and there will thus be a certain amount of deflection between the two rods 3 and 11, this being accounted for by the double pivotal action of the connecting member 85 connecting the adjacent ends of the said rods, without affecting the relative distance between the switch points, no matter what the adjusted position of the connecting member may be. During this action, the 90 bolt portion 5 will swing upon its pivots and the curved portion 9 of the cuff 8 will swing slightly through the slots 16 in the yoke 15, the threaded end 13 of the rod 11 being movable through the arcuate slot 10 95 in the curved portion of the cuff. Similar action will occur in the connecting member 17 during operation of the switch as will be readily understood from the foregoing de- 100 scription of the operation of the other connecting member and which will be due to the different angular positions of the connecting rod 19.

Having thus described my invention, what I claim is:—

1. In a device of the class described, the combination with a pair of movable switch points and operating mechanism therefor, of a pair of rods connected individually to the said switch points and disposed substan- 110 tially in transverse alinement, a connecting member adjustably mounted upon the ad-

2
jacent ends of said rods, the said member being adapted to permit relative angular movement of the said rods, and means for connecting one of the switch points with the 5 switch operating mechanism.

2. In a device of the class described, the combination with a pair of movable switch points and operating mechanism therefor, of a pair of rods secured individually to the 10 said switch points and disposed substantially in transverse alinement, a connecting member mounted upon the adjacent ends of said rods, the said member being pivotally connected to one rod for movement in one plane and connected to the other rod for movement in an angularly disposed plane, and means 15 for connecting one of said switch points with the switch operating mechanism.

3. In a device of the class described, the 20 combination with a pair of movable switch points and operating mechanism therefor, of a pair of rods secured individually to the said switch points and disposed substantially in transverse alinement, a connecting member mounted upon the adjacent ends of 25 said rods, the said member being pivotally connected to one rod for movement in one plane and connected to the other rod for movement in an angularly disposed plane, the said connecting member being longitudinally adjustable upon one of said rods, and means for connecting one of the switch 30 points to the switch operating mechanism.

4. In a device of the class described, the 35 combination with a pair of switch points and operating mechanism therefor, of a pair of rods secured individually to the said switch points in substantially transverse alinement, means for connecting one of said switch 40 points with the operating mechanism, and a connecting member including a bolt portion mounted upon the inner end of one of the said rods, a yoke portion having its extremities pivotally mounted upon the bolt portion, and a second yoke portion mounted 45 upon the adjacent end of the coacting rod and provided with alining slots in its arms slidably receiving the curved cross portion of the first yoke portion.

5. In a device of the class described, the 50 combination with a pair of switch points and operating mechanism therefor, of a pair of rods secured individually to the said switch points in substantially transverse

alinement, means for connecting one of said 55 switch points with the operating mechanism, and a connecting member including a bolt portion mounted upon the inner end of one of the said rods, a yoke portion having its extremities pivotally mounted upon the bolt portion, and a second yoke portion mounted upon the adjacent end of the coacting rod and provided with alining slots in its arms slidably receiving the curved cross portion of the first 60 yoke portion, the first 65 yoke portion being provided with an arcuate slot in its curved portion receiving the second rod.

6. In a device of the class described, the combination with a pair of switch points and 70 operating mechanism therefor, of a pair of rods secured individually to the said switch points in substantially transverse alinement, means for connecting one of said switch points with the operating mechanism, and a 75 connecting member including a bolt portion mounted for longitudinal adjustment upon the inner end of one of the said rods, a yoke portion having its extremities pivotally mounted upon the bolt portion, and a second 80 yoke portion mounted upon the adjacent end of the coacting rod and provided with alining slots in its arms slidably receiving the curved cross portion of the first yoke portion. 85

7. In a device of the class described, the combination with a pair of switch points and operating mechanism therefor, of a pair of rods secured individually to the said switch points in substantially transverse 90 alinement, means for connecting one of said switch points with the operating mechanism, and a connecting member including a bolt portion mounted upon the inner end of one of the said rods, a yoke portion having its extremities pivotally mounted upon the bolt portion, and a second portion mounted for longitudinal adjustment upon the adjacent 95 end of the coacting rod and provided with alining slots in its arms slidably receiving the curved cross portion of the first yoke portion. 100

In testimony whereof I affix my signature in presence of two witnesses.

ELIJAH F. JOHNSON.
